ENCLOSING CASING OF PROPELLERS OR
IMPELLERS

Ralph Poole, Bredbury, England

Application March 22, 1943, Serial No. 480,962
In Great Britain February 27, 1942

12. Claims. (Cl. 230—120)

This invention relates to the enclosing casing of a propeller or impeller and has for its object to improve the general efficiency of the apparatus which may be employed for various purposes.

Where a propeller or impeller rotates in a casing the clearance between the tip of each blade and the casing has a critical effect on the performance of the apparatus. This is particularly the case where the rotating member is delivering a relatively small volume of fluid and the leakage back past the blade tips and between them and the surrounding wall of the casing is of great importance.

Where a propeller fan has to operate at high pressure it may be said to behave like a badly fitting piston in a cylinder and steps have to be taken to reduce or control the flow which takes place along the wall of the cylinder or casing. In the case of an impeller whose blades are open ended with the tips free, it is customary to reduce the clearance at the tips to a minimum and it is known that an increase in maximum pressure can be obtained by joining the ends of the blades with a shrouding ring. Since the shroud itself presents an obstruction to the inflow of air at the ends of the blades it is usual to arrange that the diameter of the casing at the inlet is reduced so as to correspond approximately to the inside diameter of the shrouding ring. The edge of the inwardly projecting part of the casing is brought as close as possible to the shroud of the impeller and the face of this projecting part is hollowed out to form a groove. There is a disadvantage in this arrangement, however, since the shrouding ring gives rise to a loss of energy owing to the rotating surface which it presents close to the stationary casing. To reduce this windage loss the radial clearance between the rotating shroud and the casing is maintained as large as possible provided the gap in the axial direction can be kept small. In this arrangement there is a disadvantage in that the air leaking back past the shroud has a substantial radially inward movement and thus tends to reduce the effective diameter of the impeller interfering with the main inflow of air. Moreover, as the gap in the axial direction is made small the velocity of the inwardly directed jet tends to become high. In the improved arrangement the use of the shrouding ring is dispensed with and by encouraging and controlling the circulation at the free tips of the blades an effective sealing can be effected.

According to this invention the fixed casing surrounding the propeller or impeller has an an-

nular thickening forming a flange, fillet or similar part which functions as a deflector for fluid leaking back past the tips of the impeller blades, this deflector member projecting inwards from the casing on the low pressure side of the impeller adjacent to the leading edges of the blades. Preferably the face of the annular deflector which is directed towards the blades of the impeller is formed concave or hollowed out. If desired a second and similar deflector may be disposed in a similar position in the casing adjacent to the edges of the blades on the downstream or high pressure side of the impeller. The radial width of the deflector is conveniently though not necessarily equal to about twice the radial distance between the tips of the blades and the wall of the casing surrounding the impeller. The face of the deflector which is directed towards the impeller should be a smooth surface of revolution about the impeller axis. This surface may be flat, but as mentioned it is preferably concave, the curvature for example being part of a parabola whose axis is parallel to the axis of the impeller. The circulation of the fluid which leaks back over the tips of the blades of the impeller may be assisted by placing in the hollow face of the deflector an annular member which serves to direct the desired fluid flow. The fluid will tend to pass over and around this guide ring within the hollow face of the deflector thus reversing its direction of flow.

The operation of the device may be explained as follows. The fluid leaking back past the tips of the blades is rotating at a considerable speed about the axis of the impeller. This is particularly marked in the case of a high pressure impeller moving a relatively small quantity of fluid, where the axial velocity of the fluid remains fairly small compared with the circumferential velocity. The thrust of the blades on the fluid in the axial direction decreases as the rotational velocity of the fluid increases, and the thrust becomes zero when the fluid rotates at the same rate as the blades. The excess pressure of the fluid on the high pressure side of the impeller always provides a tendency for back leakage, but normally the axial thrust will only be overcome and leakage occur when the rotational velocity of the fluid has increased sufficiently to permit this. In the ordinary way fluid which has leaked back past the impeller in this way is subsequently drawn through the impeller again, but while it has been on the low pressure side it will have lost most of its rotational velocity with the result that work must be expended when the fluid is passed

again through the impeller in order to restore rotary motion to this part of the fluid just as if it was a part of the main body of fluid at the intake. If, however, the fluid which has leaked back can be returned through the impeller without appreciable loss in its rotational velocity, it will not be necessary to expend much work on it during its second passage through the impeller. This will be effected by a deflector constructed and arranged in accordance with this invention, since the fluid which has leaked back has its direction of movement reversed by the deflector being assisted by the guide ring without appreciably reducing its rotational velocity. It is thus possible to promote a circulation of the leakage fluid since substantially the same fluid after leaking back along the wall of the casing will have its direction of flow reversed by and in the deflector and thereby be caused to pass forwards again through the impeller at a small distance radially inwards from the wall of the casing, this part of the fluid then again leaking backwards. Although this may be described as a secondary circulation in a radial plane relatively to the impeller axis, the fluid is all the time rotating about that axis. Thus the actual path of the fluid, which in effect provides an artificial seal, tends to be a complex spiral or vortex having as its core a circle which is substantially coincident with the path followed by the tips of the blades of the impeller.

This secondary circulation may be increased if, as indicated, a similar deflector is arranged on the high pressure side of the impeller. This should have its face which is directed backwards towards the blades formed with a concave surface of revolution. Though this may detract in some degree from the efficiency of the impeller when delivering large volumes of fluid at low pressure, on the other hand it will improve the efficiency when delivering relatively small volumes at high pressure, and will substantially increase the pressure obtainable when the delivery approaches zero.

The accompanying drawing illustrates by way of example two alternative arrangements embodying the present invention. In the drawing,

Figure 1 is a longitudinal sectional elevation showing an impeller and the casing enclosing it as adapted for use for example with air or other gas.

Figure 2 is a similar view of a screw pump with the invention applied thereto.

Referring to Figure 1, the impeller there shown comprises blades A mounted on a boss B to which rotation is imparted in some suitable manner. The casing C which immediately surrounds the impeller in this case is cylindrical and has connected to it a flared member D constituting the suction entry to the impeller. This member has an external flange D¹ which is bolted up to a flange C¹ on the end of the casing C. The inner part D² of the member D forms a deflector for the air which leaks back past the tips of the blades A. This inner part D² is a smooth continuation of the belled mouth D of the entry member and being of less diameter lies within and is spaced from the end portion of the casing C between which and the part D² is thus formed an annular space E. The external part of the member D which is adjacent to the flange D¹ and faces the space E is hollowed as at D³ so as to form a smooth curve for the wall of the annular space E which will conduce to the return flow of the fluid which may leak back past the tips of the blades A. This circulatory flow is assisted

by a ring F which may be provided and is suitably mounted by way of example, by means of spider or bracket elements F', in the annular space E intermediate between the wall of the casing C and the outer surface of the deflector D². The air flow from the tips of the blades will thus tend to pass over the outside of the ring F and being deflected by the curved end D³ of the space E will return within the ring F to be again delivered by the impeller.

A definite circulation of this fluid may be assisted or induced by providing on the downstream or high pressure side of the impeller A a thickening G on the inner wall of the casing C as shown in dotted lines. This thickening or fillet G is externally smoothly curved and its face which is directed towards the blades A is concave as at G¹. The fluid leaking back past the blades can thus circulate around the ring F in the annular space E and being delivered forwardly will be returned by the hollow G¹ in the face of the fillet G.

Turning now to the construction shown in Figure 2, this comprises an impeller formed to act as a screw pump and enclosed in a casing. The latter is built up of several parts of which one H is shaped to take the fluid delivered by the impeller and lies on the downstream side beyond the impeller blades A¹. The next part J immediately surrounds the blades A¹ and beyond this is a ring K formed internally to act as a deflector according to this invention. A spacing ring L is interposed between this ring K and the flared suction entry member M. All these parts are suitably bolted up together. The blades A¹ of the impeller may be shaped as shown and they are carried by a boss B¹ on a shaft B² which is driven in some convenient manner. Internally the diameter of the deflector ring K is less than that of the adjacent part of the casing member J which surrounds the impeller blades and thus it has a part K¹ which projects somewhat into the intake to the pump. On the side which faces the blades this part K¹ is hollowed out as at K² and in this hollow is preferably placed and suitably fixed a flat ring F¹. Fluid leaking back between the tips of the blades A¹ and the interior of the surrounding casing J will enter the hollow K² in the face of the deflector member K¹ and with the assistance of the ring F¹ will be caused to reverse its direction of flow so that it will again be delivered by the impeller. On the suction side the interior of the flared member M is conveniently provided with a thickening or lining M¹, which may be made of some suitable plastic material and moulded to the desired contour so as to give a smooth entry reducing the diameter to that of the interior K¹ of the deflector ring K. It is convenient to interpose the spacing ring L between the deflector ring K and the suction entry member M the ring L extending on the suction side the thickening effect within the casing of the deflector member K¹. The arrangement does not interfere with the normal flow of the fluid to the impeller while inducing or assisting a circulation at the blade tips which will tend to act as a seal. This construction is more especially designed to enable an existing pump structure to be modified and provided with the present invention by the interposition of the deflector ring K and the spacing ring L between the flared suction entry member M and the casing J around the impeller blades.

In this case, as in the construction shown in Figure 1, if desirable a somewhat similar de-

flector may be disposed adjacent to the blades A¹ on the downstream side of the impeller.

What I claim as my invention and desire to secure by Letters Patent is:

1. A rotary pump or fan of the axial flow type comprising in combination an impeller having open ended blades with their tips free; a casing enclosing the impeller and having a suction entry part of the wall of which is of larger diameter than the remainder, and a thickening of the wall of said casing which projects inwardly as an annulus having a side remote from and a side adjacent the impeller adjacent to the tips of the impeller blades on the low pressure side of the impeller, this projecting annulus having a face which is concave and being directed towards the impeller serving to deflect first inwards and then again towards the impeller the flow of fluid leaking back past the tips of the blades from the high pressure to the low pressure side of the impeller, the annulus on the side remote from the impeller sloping away to the part of the wall of the suction entry of the casing which has a larger diameter.

2. A rotary pump or fan of the axial flow type comprising in combination an impeller having open ended blades with their tips free; a casing enclosing the impeller; a thickening of the wall of said casing which projects inwardly as an annulus adjacent to the tips of the impeller blades on the low pressure side of the impeller; this projecting annulus having a face which is concave and is directed towards the impeller; and a ring member mounted in the annular concavity in the said face of the said projecting annulus; this ring member lying between and being spaced radially from the opposed sides of the concavity whereby fluid leaking back past the tips of the blades from the high pressure to the low pressure side of the impeller is deflected and passing in the concavity round the said ring member is again directed towards the impeller.

3. A rotary pump or fan of the axial flow type comprising in combination an impeller having open ended blades with their tips free, a casing enclosing the impeller and having a suction entry part of the wall of which is of larger diameter than the remainder and constituted by a part which immediately surrounds the impeller adjacent to the tips of the blades; a flared part which is on the low pressure side of the impeller and serving as the suction entry and a part on the high pressure side of the impeller through which the fluid is delivered by the impeller; an annulus which projects into the said suction entry from the wall of the casing of which it constitutes a thickening; this projecting annulus having a face which is concave and is directed towards the impeller, and a ring member mounted in the annular concavity in the said face of the said projecting annulus this ring member lying between and being spaced radially from the opposed sides of the concavity whereby fluid leaking back past the tips of the blades from the high pressure to the low pressure side of the impeller is deflected and passing in the concavity round the said ring member is again directed towards the impeller; the said projecting annulus on the suction side thereof sloping away to the wall of larger diameter of the said suction entry part of the casing; and a second annulus which projects as a thickening of the wall into the said part of the casing on the delivery and high pressure side of the impeller this annulus lying adjacent to the tips of the impeller blades and having a face which is concave and being directed towards the impeller tends to deflect and assist in a circulation of the fluid which leaks back past the tips of the blades to the low pressure side of the impeller and is there caused by the said projecting annulus on the low pressure side of the impeller to return towards the high pressure side.

4. A rotary pump or fan of the axial flow type comprising in combination an impeller having open ended blades with their tips free; a casing enclosing the impeller, a thickening of the wall of said casing which projects inwardly as an an-

nulus adjacent to the tips of the impeller blades on the low pressure side of the impeller, this projecting annulus having a face which is concave and is directed towards the impeller; a ring member mounted in the annular concavity in the said face of the said projecting annulus this ring member lying between and being spaced radially from the opposed sides of the concavity whereby fluid leaking back past the tips of the blades from the high pressure to the low pressure side of the impeller is deflected and passing in the concavity round the said ring member is again directed towards the impeller, and a second thickening of the wall of the casing which projects inwardly as an annulus adjacent to the tips of the impeller blades on the high pressure side of the impeller, this second projecting annulus having a face which is concave and being directed towards the impeller tends to deflect and assist in the circulation of fluid which leaks past the tips of the blades to the low pressure side of the impeller and is there caused by the said projecting annulus on the low pressure side of the impeller to return towards the high pressure side.

5. A rotary pump or fan of the axial flow type comprising in combination an impeller having open ended blades with their tips free; a casing enclosing the impeller and constituted by a part which immediately surrounds the impeller adjacent to the tips of the blades, a part flared which is on the low pressure side of the impeller and serves as the suction entry and a part on the high pressure side of the impeller through which the fluid is delivered by the impeller; an annulus which projects into the said suction entry from the wall of the casing of which it constitutes a thickening; this projecting annulus having a face which is concave and is directed towards the impeller, a ring member mounted in the annular concavity in the said face of the said projecting annulus this ring member lying between and being spaced radially from the opposed sides of the concavity whereby fluid leaking back past the tips of the blades from the high pressure to the low pressure side of the impeller is deflected and passing in the concavity round the said ring member is again directed towards the impeller, the said projecting annulus on the suction side thereof sloping away to the wall of larger diameter of the said suction entry part of the casing; and a second annulus which projects as a thickening of the wall into the said part of the casing on the delivery and high pressure side of the impeller this annulus lying adjacent to the tips of the impeller blades and having a face which is concave and being directed towards the impeller tends to deflect and assist in a circulation of the fluid which leaks back past the tips of the blades to the low pressure side of the impeller and is there caused by the said projecting annulus on the low pressure side of the impeller to return towards the high pressure side.

6. A rotary pump or fan of the axial flow type comprising in combination an impeller having open ended blades with their tips free; a casing enclosing the impeller and constituted by a part which immediately surrounds the impeller adjacent to the tips of the blades with an extension of this part on the high pressure side of the impeller through which the fluid is delivered; a separate part serving as the suction entry; and between this part and the casing part immediately surrounding the impeller a separate inserted casing section; means whereby these separate parts of the casing are connected together, an annulus

which projects into the said suction entry from the wall of the said separate inserted casing section of which wall the annulus constitutes a thickening, the projecting annulus having a face which is concave and is directed towards the impeller, and a ring member mounted in the annular concavity in the said face of the said projecting annulus this ring member lying between and being spaced radially from the opposed sides of the concavity whereby fluid leaking back past the tips of the blades from the high pressure to the low pressure side of the impeller is deflected and passing in the concavity round the said ring member is again directed towards the impeller.

7. A rotary pump or fan of the axial flow type comprising in combination an impeller comprising a single blade set having open ended blades with their tips free, a single concave face system including a casing enclosing the impeller and constituted by a part which immediately surrounds the impeller adjacent to the tips of the blades, a flared part which is on the low pressure side of the impeller and serves as the suction entry and a part on the high pressure side of the impeller through which the fluid is delivered by the impeller, and an annulus which projects into the said suction entry from the wall of the casing of which it constitutes a thickening, this annulus having a face directed towards the tips of the impeller blades to which it is adjacent, this face serving to deflect inwards the flow of fluid leaking back past the tips of the blades from the high pressure to the low pressure side of the impeller, the annulus on the suction side thereof sloping away to the part of the wall of the said suction entry of the casing which has a larger diameter, the face of the said annulus which is directed towards the impeller is concave and serves to deflect first inwards and then again towards the impeller the flow of fluid leaking back past the tips of the blades.

8. A rotary pump or fan of the axial flow type comprising in combination the parts set out in claim 7 in which the face of the said annulus which is directed towards the impeller is concave and serves to deflect first inwards and then again towards the impeller the flow of fluid leaking back past the tips of the blades.

9. A rotary pump or fan of the axial flow type comprising in combination an impeller comprising a single blade set having open ended blades with their tips free, a single concave face system including a casing enclosing the impeller, a thickening of the wall of this casing which projects inwardly as an annulus adjacent to the tips of the impeller blades on the low pressure side of the impeller, this projecting annulus having a face which being directed towards the impeller serves to deflect inwards the flow of fluid leaking back past the tips of the blades from the high pressure to the low pressure side of the impeller, and a second thickening of the wall of the casing which projects inwardly as an annulus adjacent to the tips of the impeller blades on the high pressure side of the impeller, this second projecting annulus having a face which is directed towards the impeller and tends to deflect and assist in a circulation of the fluid which having leaked back past the tips of the blades has been deflected by the said projecting annulus on the low pressure side of the impeller and caused to be returned towards the high pressure side by the action of the blades, the face directed towards the impeller of the said annulus which projects on the low pressure side adjacent to the blades

of the impeller is concave and serves to direct first inwards and then again towards the impeller the flow of fluid leaking back past the tips of the blades, and the face directed towards the impeller of the said second annulus which projects on the high pressure side of the impeller is also concave and tends to deflect and assist in the circulation of fluid which leaks past the tips of the blades to the low pressure side of the impeller.

10. A rotary pump or fan of the axial flow type comprising in combination an impeller comprising a single blade set having open ended blades with their tips free, a single concave face system including a casing enclosing the impeller and constituted by a part which immediately surrounds the impeller adjacent to the tips of the blades, a flared part which is on the low pressure side of the impeller and serves as the suction entry and a part on the high pressure side of the impeller through which the fluid is delivered by the impeller, an annulus which projects into the said suction entry from the wall of the casing of which it constitutes a thickening, this annulus having a face directed towards the tips of the impeller blades to which it is adjacent, this face serving to deflect inwards the flow of fluid leaking back past the tips of the blades from the high pressure to the low pressure side of the impeller, the annulus on the suction side thereof sloping away to the part of the wall of the said suction entry of the casing which has a larger diameter, and a second annulus which projects as a thickening of the wall into the said part of the casing on the delivery and high pressure side of the impeller, this annulus lying adjacent to the tips of the impeller blades and having a face which is directed towards the impeller and tends to deflect and assist in a circulation of the fluid which having leaked back past the tips of the blades has been deflected by the said projecting annulus on the low pressure side of the impeller and caused to be returned towards the high pressure side by the action of the blades, the face directed towards the impeller of the said annulus which projects on the low pressure side of the impeller adjacent to the blades is concave and serves to direct first inwards and then again towards the impeller the flow of fluid leaking back past the tips of the blades, and the face directed towards the impeller of the said second annulus which projects on the high pressure side of the impeller is also concave and tends to deflect and assist in the circulation of fluid which leaks past the tips of the blades to the low pressure side of the impeller.

11. A rotary pump or fan of the axial flow type comprising in combination an impeller comprising a single blade set having open ended blades with their tips free, a single concave face system including a casing enclosing the impeller and constituted by a part which immediately surrounds the impeller adjacent to the tips of the blades, a flared part which is on the low pressure side of the impeller and serves as the suction entry and a part on the high pressure side of the impeller through which the fluid is delivered by the impeller, an annulus which projects into the said suction entry from the wall of the casing of which it constitutes a thickening, this annulus having a face directed towards the tips of the impeller blades to which it is adjacent, this face serving to deflect inwards the flow of fluid leaking back past the tips of the blades from the high pressure to the low pressure side of the impeller.

impeller, the annulus on the suction side thereof sloping away to the part of the wall of the said suction entry of the casing which has a larger diameter, and a second annulus which projects as a thickening of the wall into the said part of the casing on the delivery and high pressure side of the impeller, this annulus lying adjacent to the tips of the impeller blades and having a face which is directed towards the impeller and tends to deflect and assist in a circulation of the fluid which having leaked back past the tips of the blades has been deflected by the said projecting annulus on the low pressure side of the impeller and caused to be returned towards the high pressure side by the action of the blades, the side of the said second annulus remote from the impeller slopes away to the wall of larger diameter of the said part of the casing through which the fluid is delivered by the impeller.

12. A rotary pump or fan of the axial flow type comprising in combination an impeller comprising a single blade set having open ended blades with their tips free, a single concave face system including a casing enclosing the impeller, a part of which casing immediately surrounds the impeller adjacent to the tips of the blades, a flared part which is on the low pressure side of the impeller and serves as the suction entry and a part on the high pressure side of the impeller through which the fluid is delivered by the impeller, an annulus which projects into the said suction entry from the wall of the casing of which it constitutes a thickening, this annulus

having a face directed towards the tips of the impeller blades to which it is adjacent, this face serving to deflect inwards the flow of fluid leaking back past the tips of the blades from the high pressure to the low pressure side of the impeller, the annulus on the suction side thereof sloping away to the part of the wall of the said suction entry of the casing which has a larger diameter, and a second annulus which projects as a thickening of the wall into the said part of the casing on the delivery and high pressure side of the impeller, this annulus lying adjacent to the tips of the impeller blades and having a face which is directed towards the impeller and tends to deflect and assist in a circulation of the fluid which having leaked back past the tips of the blades has been deflected by the said projecting annulus on the low pressure side of the impeller and caused to be returned towards the high pressure side by the action of the blades, the wall of that part of the casing which lies on the high pressure side of the impeller is thickened forming a second inwardly projecting annulus adjacent to the tips of the impeller blades, this second projecting annulus having a face which is directed towards the impeller and tends to deflect and assist in a circulation of the fluid which having leaked back past the tips of the blades has been deflected by the said projecting annulus on the low pressure side of the impeller and caused to be returned towards the high pressure side by the action of the blades.

RALPH POOLE.
